UNITED STATES PATENT OFFICE.

ADELBERT A. THOMAS, OF CHICAGO, ILLINOIS, ASSIGNOR TO CRESO MANUFACTURING CO., OF CHICAGO, ILLINOIS, A CORPORATION OF ILLINOIS.

MACHINE FOR COVERING METALLIC BOXES.

1,377,232.

Specification of Letters Patent. Patented May 10, 1921.

Application filed September 29, 1920. Serial No. 413,594.

To all whom it may concern:

Be it known that I, ADELBERT A. THOMAS, a citizen of the United States, and a resident of Chicago, in the county of Cook and 5 State of Illinois, have invented certain new and useful Improvements in Machines for Covering Metallic Boxes, of which the following is a full, clear, and exact description.

The invention relates to machines for covering metallic boxes and its object is to provide improved infolding mechanism by which the covering may be lapped and held around the edge of the box, which is simple in construction and efficient in operation.

15 The invention consists in the several novel features hereinafter set forth and more particularly defined by claims at the conclusion hereof.

In the drawings: Figure 1 is a side elevation 20 of a machine embodying the invention, parts being shown in section. Fig. 2 is a perspective of the upper die and parts connected thereto. Fig. 3 is a section taken on line 3—3 of Fig. 5. Fig. 4 is a section taken 25 on line 4—4 of Fig. 5. Fig. 5 is a vertical section through the upper die.

The invention is illustrated as applied to a machine comprising a supporting frame 10 which is secured to a work-table 11 in 30 any suitable manner and a base 12 which is adapted to support a guide 13 in which the lower die carrier 14 is suitably held. The frame also comprises a standard 15 having a guideway formed therein for the stem 17 35 of the upper die.

The lower die comprises a holder-block 20 shaped to fit into the boxes to be covered and fixed to a post 19 which is vertically 40 slideable in the carrier 14. Block 20 conforms substantially to the shape of the inside of the box so that the latter can be placed over and will be held around the block. A cover holder member 24 surrounds the block 20, is formed with an opening 25 which has its sides properly spaced from the block, so that the box-sides can be dropped onto the block. The top of member 24 is 45 adapted to support a sheet of suitable covering material of the desired shape necessary to cover the box and is provided with a gage 24' to position the sheet. A bottom plate 27 is secured to member 24. Posts 28 extend downwardly through, and are vertically movable in, the carrier 14 to permit 50 said member to slide vertically relatively to

the carrier. Plate 27 is extended to underlie block 20 to limit the upward movement of the socket member relatively to the block so that normally the top of member 24 will be disposed substantially flush with the top 60 of the box on the block 20. Springs 29 between plate 27 and carrier 14 press member 24 normally upward and permit said member to recede as the upper die forces the cover around the sides of the box on the 65 block. A device to provide cumulative pressure or force to the member 24 when it is forced downwardly by the upper die comprises a rod 80 secured to plate 13', a spring 81 engaging a nut 82 on said rod and a 70 plate 83 engaged by the upper end of the spring and vertically slidable on posts 28.

The upper die comprises a plate 32, a body 33 and a bottom plate 34 all secured together and to the lower end of stem 17. An opening 35 is formed in plate 34 and body 33 which is shaped to conform to the sides of the box with the cover around it. A plunger 37 conforming to the shape of the top of the box is slidably mounted in opening 80 35 so that the covered box in said opening may be ejected from the upper die. Said die is adapted, when operated in conjunction with the block 20 and socket-member 25, to fold the cover-sheet around the sides of the 85 box. During the folding operation, plate 34 will engage the spring-pressed holder 24 and force it downwardly against the force of springs 29, 81 to permit the upper die to force the cover around the box. 90

A series of infolders 38 are radially slideable in body 33 and their inner ends conform normally to the form of the opening 35 and to the box. These are adapted to engage the cover after it has been placed 95 around the box and lap the marginal portions of the covering inwardly under the edge of the box. These folders 38 are conjointly operable by a U-shaped shifter 39 which has its sides slidably held in grooves 100 33' in the body 33 and has depending pins secured thereon which extend through inclined slots 40 in the infolders respectively. The cross-bar of shifter 39 is disposed outside of the body 33 so that it is readily 105 accessible. A lever 42 pivoted to the body of the upper member is operatively connected by a pin and slot 42'. A spring 43 is applied to the shifter to retract it and normally hold the folders 38 retracted or 110

inoperative. A pivoted latch 44 is adapted to engage a lug 45 on shifter 39 to normally lock the shifter so that the infolders, when they have been shifted inwardly, will be automatically locked to retain the cover lapped around the edge of the box until the upper die is again lowered to press the cover against the inside of the box by other mechanism. This latch will be automatically released when the upper die has been lowered by a trip 46 which is fixed to the guide 13 and has an inclined upper edge 47 adapted to engage an inclined edge 48 on the latch 44. As a result, it is not necessary for the operator to hold the infolders in operative position.

A stem 56 is secured to the ejector 37 and is slidable in the stem 17 of the upper die. A spring 57 is applied to hold member 37 normally at the top of the opening 35 in the member 33. Any suitable mechanism may be provided for raising and lowering the stem 17 and for lowering the stem 17 in the upper die to eject the box.

In operation, the box will be placed on the block 20 and a covering sheet 26 will be laid on the member 24. The upper die will then be lowered to cause the cover-sheet to be laid around sides of the box, member 24 being forced downwardly away from the block 20 by the plate 34 of the upper die. Next, the upper die will be retracted and during this retraction, the box and cover will remain in the opening 35 on the upper die. During this retraction, the operator will shift lever 42 to conjointly operate the infolders inwardly which will be automatically locked to retain the covering folded over the edges of the box by the latch 44.

The succeeding steps in this box-covering operation may be performed by suitable mechanism, as well understood in the art, and which forms no part of the present invention.

The invention exemplifies infolding mechanism for box covering machines which is simple in construction and in which the shifter is slidably mounted to move in a rectilinear path and in which a portion of the shifter, to which the operating mechanism is connected, is disposed outside of the body in which the shifter slides. Also such a structure is adapted to be automatically released. The invention is not to be understood as restricted to the details set forth, since these may be modified within the scope of the ap-

pended claims, without departing from the spirit and scope of the invention.

Having thus described the invention, what I claim as new and desire to secure by Letters Patent is:

1. In a machine for covering cases, the combination of coöperating dies one of which is provided with an opening with the cover folded around its sides, a series of 65 slidable folders for folding the edge of the covering over the edge of the box, and a shifter for said folders comprising a member operatively connected to the folders and slidable in a rectilinear path. 70

2. In a machine for covering cases, the combination of coöperating dies one of which is provided with an opening with the cover folded around its sides, a series of 75 slidable folders for folding the edge of the covering over the edge of the box, and a shifter provided with sides slidably mounted in the latter die and a connecting member outside of the die.

3. In a machine for covering cases, the 80 combination of coöperating dies one of which is provided with an opening with the cover folded around its sides, a series of 85 slidable folders for folding the edge of the covering over the edge of the box, a U-shaped shifter for said folders slidably mounted in the latter die and having its connecting member disposed outside of the die.

4. In a machine for covering cases, the 90 combination of coöperating dies one of which is provided with an opening with the cover folded around its sides, a series of 95 slidable folders for folding the edge of the covering over the edge of the box, and a shifter mounted to slide in a rectilinear path in the latter die and having a member outside thereof, and a lever pivoted to the latter die and operatively connected to the shifter. 100

5. In a machine for covering cases, the combination of coöperating dies one of which is provided with an opening with the cover folded around its sides, a series of 105 slidable folders for folding the edge of the covering over the edge of the box, a shifter slidably mounted in the latter dies and operatively connected to operate the infolders, and a pivoted latch adapted to automatically lock the shifter.

ADELBERT A. THOMAS.
